ROLLING MILL

Christian E. Grosser, Cambridge, Mass., and Herman A. Bondeson, Providence, R. I., assignors to Standard Machinery Company, Cranston, R. I., a corporation of Rhode Island

Application November 23, 1940, Serial No. 366,864

18 Claims. (Cl. 80—32)

The present invention relates to improvements in rolling mills and more particularly to a method of driving the reduction rolls and individual hydraulic driving means for each of the units of tandem mills.

It has heretofore been proposed to provide hydraulic drives for the plurality of units of a rolling mill but in such previous drives the speed of the reduction rolls or the speed ratio between these sets of reduction rolls is maintained constant while the torque of the rolls is permitted to vary. Such prior art drives usually comprise a constant displacement fluid motor for driving the reduction rolls and the speed is determined by the amount of motive fluid supplied thereto. The motive fluid for the motor is usually supplied by a pump and the speed of the motor is controlled by adjusting the displacement of the pump. Thus, the driving motors for a plurality of sets of reduction rolls apply from a minimum to a maximum of torque to the work to maintain the particular speed ratio between successive sets of reduction rolls. Adjustment of the various pumps to coordinate the speed of the various rolling units is very difficult as any stretch or slack in the stock between successive sets of reduction rolls, due to discrepancies in the speed ratios and variations in the elongation of the rolled material, accumulates during operation of the mill.

One of the objects of the present invention is to provide a method of and means for driving the plurality of reduction roll units of a rolling mill with a predetermined constant torque slightly in excess of the rolling effort whereby to maintain a uniform tension on and alignment of the stock between the units while permitting the speed of the units to vary.

Another object of the invention is to provide a hydraulic drive for each of the plurality of reduction roll units of a tandem mill which will maintain the pressure of the motive fluid constant for any particular adjustment.

Another object of the invention is to provide a hydraulic drive of the type indicated having a fluid motor and supply pump with a manually adjustable relief valve between the motor and pump for automatically bleeding the motive fluid to maintain its pressure constant.

Another object of the invention is to provide a rolling mill having an adjustable speed drive for the break-down rolls and hydraulic drives of the type indicated for the plurality of sets of reduction rolls.

Another object of the invention is to provide

a rolling mill of the type indicated having a hydraulic drive for operating the take-up reel to apply a constant tension on the rolled stock as it is wound on the reel.

5 Another object of the invention is to provide a rolling mill of the type indicated having hydraulic operating means for relatively traversing the take-up reel and stock to deposit the stock in superimposed layers of adjacent coils on the reel.

10 Still another object of the invention is to provide hydraulic drives of the type indicated which are of comparatively simple construction and adapted to be easily and quickly adjusted to drive the reduction roll units with a predetermined torque whereby to maintain the proper tension on the stock between units.

15 Further objects of the improvement are set forth in the following specification which describes a preferred embodiment of the invention and several modified forms of construction thereof, by way of example, as illustrated by the accompanying drawings. In the drawings:

20 Fig. 1 is a side elevational view of a rolling mill incorporating the novel features of the present invention;

25 Fig. 2 is a plan view of the rolling mill showing the series of sets of reduction roll and wind-up reel units arranged in tandem and the individual driving means for each unit;

30 Fig. 3 is a diagrammatic view of the fluid circuits of the series of hydraulic drives showing the relief valves for controlling the pressure of the motive fluid in each circuit;

35 Fig. 4 is a transverse sectional view taken on line 4—4 of Fig. 2 showing the mounting for the edger rolls to adapt them for adjustment;

40 Fig. 5 is a diagrammatic view of the fluid circuit of a modified form of hydraulic drive for the take-up reel showing control means for automatically adjusting the displacement of a variable displacement fluid motor in accordance with the increase in the effective diameter of the reel as the stock winds up thereon;

45 Fig. 6 is a diagrammatic view of the fluid circuit of another modified form of hydraulic drive for the take-up reel showing a different form of control means for automatically adjusting the amount and pressure of the motive fluid supplied to a constant displacement fluid motor;

50 Fig. 7 is a diagrammatic view of a fluid circuit of still another form of hydraulic drive for the take-up reel showing a control means for automatically adjusting the displacement of the supply pump;

Fig. 8 is a diagrammatic view of the fluid circuit of a hydraulic drive and control means for relatively traversing the reel and stock showing the relationship of the parts during traverse in one direction; and

Fig. 9 is a view similar to Fig. 8 showing the relative positions of the parts during traverse in the opposite direction at a later stage in the winding operation.

The present invention relates in general to a method of and means for driving each of the units of a tandem rolling mill to maintain a substantially constant tension on the stock between adjacent sets of reduction rolls and between the last set of rolls and the take-up reel. The method consists in driving the first set of reduction rolls with a variable speed drive which may be manually adjusted to control the speed of the stock feeding through the mill, and driving the successive sets of reduction rolls with a predetermined constant torque slightly in excess of the rolling effort whereby a substantially constant tension is maintained between adjacent sets of reduction rolls and the speed of the reduction rolls is permitted to vary to automatically adjust itself to the speed of the stock.

The rolling mill to which the present improved method is applied comprises a set of break-down rolls, a plurality of sets of reduction rolls and a take-up reel arranged in tandem to act on a single continuous strip of stock. The break-down rolls are directly driven by a variable speed prime-mover which controls the speed of the stock through the rolling mill. The plurality of sets of reduction rolls and take-up reels are operated by individual hydraulic drives. The fluid motors of the individual hydraulic drives for the reduction rolls are responsive to the pressure of the motive fluid to drive the rolls with a predetermined constant torque, and manually operated relief valves are provided in the fluid circuits for controlling the pressure of the motive fluid. The relief valves of the individual hydraulic drives are adjusted to cause the sets of reduction rolls to apply a predetermined constant torque slightly in excess of the rolling effort whereby the speed of the rolls adjusts itself to the speed of the stock and maintains a predetermined tension on the stock between the sets of reduction rolls and between the last set of rolls and the take-up reel. Preferably, the hydraulic drive for the take-up reel comprises a constant horsepower fluid motor with control means for gradually varying its displacement or the amount of fluid supplied thereto to decrease the angular speed of the reel in proportion to the increase in the diameter of the layers of stock wound thereon whereby to maintain a uniform tension on the stock throughout the winding. The invention also contemplates the use of hydraulic driving means for relatively traversing the take-up reel and stock to wind the latter in superimposed layers of closely adjacent coils on the reel.

Referring to the accompanying drawings, the rolling mill is herein illustrated as comprising a frame 2 in which are journaled a set of break-down rolls 3, a set of edger rolls 4 and a set of finishing rolls 5. It will be understood, however, that the rolling mill may incorporate different arrangements of reducing rolls besides that herein illustrated. The break-down rolls 3 are journaled one above the other in suitable bearings in the frame 2 and so arranged as to adapt them to be adjusted toward and away from each other by the hand-wheel 6 and reduction gearing 7 as

will be understood by those skilled in the art. The opposite break-down rolls 3 are geared to each other and driven by a drive-shaft 8.

The edger rolls 4 are arranged in laterally spaced relationship for rotation about vertical axes and are mounted and driven in a novel manner to adapt them for relative adjustment, as illustrated in Figs. 2 and 4. The edger rolls 4 are keyed to shafts 10 journaled at opposite sides of the frame 2 in anti-friction bearings 11 carried by bearing-blocks 12. The bearing-blocks 12 for the opposite edger rolls 4 are slideable in suitable ways 13 in the frame 2 of the machine and adapted to be moved toward and away from each other by screws 14 having their ends extending into tapped holes 15 in the blocks and their opposite ends screwed into tapped holes 16 in bearings on the frame 2. The screws 14 have threads of opposite pitch cooperating with the blocks 12 and bearing holes 16 whereby rotation of the screws causes sliding movement of the blocks on the ways 13. For simultaneously rotating the screws 14 a gear 17 pinned to each screw meshes with pinions 18 on a shaft 19 extending parallel to the axes of the screws and having a hand-wheel 20 at one end. Thus the edger rolls 4 may be adjusted toward or away from each other by turning the hand-wheel 20 to rotate the shaft 19.

The edger rolls 4 are driven in any position of adjustment by means of face gears 24 on the projecting ends of the shafts 10 which mesh with pinion gears 25 on a drive shaft 26. The drive shaft 26 is journaled in suitable bearings in the frame 2 and arranged transversely of the axes of the roll-shafts 10, the pinion gears 25 being made sufficiently extended to adapt the face gears 24 to slide therealong and mesh therewith in any position of adjustment.

The finishing rolls 5 are similar to the break-down rolls 3, being arranged one above the other, geared to each other and driven by a drive shaft 27 through reduction gearing 28, see Fig. 1.

A take-up reel 30 is provided at the delivery end of the mill, being arranged in tandem with the break-down rolls 3 and reducing rolls 4 and 5 to wind up the rolled stock. As herein illustrated the take-up reel 30 is provided as a separate unit, but it will be understood that it may be constructed as an integral part of the rolling mill. As illustrated in Figs. 1 and 2 the take-up reel 30 comprises a frame 31 having a shaft 32 journaled therein with one end extending outwardly from the frame and mounting a drum 33 on which the stock is wound. The drum 33 may be removable from the shaft 32 together with a roll of the finished stock thereon or it may be rigidly attached to the shaft and provided with peripheral grooves to adapt wires to be placed around the coil of wound stock to bind it for removal from the drum. The shaft 32 has a worm-wheel 34 keyed thereto which meshes with a worm 35 on a drive shaft 36.

The break-down rolls 3 are directly connected to a prime mover 39 through a coupling 40. Although the prime mover 39 may take other forms it is preferably a direct current, variable speed, electric motor. By adjusting suitable resistances and load conditions the speed of the break-down rolls can be regulated through a wide range and when once adjusted their speed determines the speed of the stock through the rolling mill. The sets of edger rolls 4, finishing rolls 5 and the take-up reel 30 are operated from a second prime-mover 41 through individual hydraulic drives.

Although the prime mover 41 may also take other forms, preferably it is an alternating current, constant speed type of electric motor having shaft extensions at each end. The separate electric motors 39 and 41 are controlled by a single plunger type switch 42 for simultaneously opening or closing the separate circuits for the motors to adapt the reduction roll and take-up reel units to be simultaneously started and stopped to thread the stock through the individual units at the beginning of a rolling operation, see Fig. 3.

The hydraulic drive for the edger rolls 4 comprises a pump 45 driven by one of the shaft extensions of the electric motor 41 and a fluid motor 46 connected to the drive shaft 26 for the edger rolls through a coupling 47. The pump 45 draws motive fluid through an intake manifold 48 connected to a supply tank 49 and discharges it under pressure to a conduit 50 connecting the pump and motor 46. The motive fluid is discharged from the fluid motor 46 through an exhaust manifold 51 which, through a conduit 52, returns the motive fluid to the tank 49.

The hydraulic drives for the finishing rolls 5 and take-up reel 30 are identical with that described for the edger rolls 4, comprising pumps 53 and 54 driven from one or the other of the shaft extensions of the motor 41 and drawing the motive fluid through the intake manifold 48 and discharging it under pressure through conduits 55 and 56 to fluid motors 57 and 58. The motive fluid is discharged from the motors 57 and 58 through the exhaust manifold 51. The fluid motors 57 and 58 are connected by couplings 59 and 60 to the drive shafts 27 and 36, respectively, for the finishing rolls 5 and the take-up reel 30.

In accordance with the present invention the pumps 45, 53 and 54 may be of any suitable positive-displacement construction, such as gear or vane type, or of any type having a low pulsation characteristic for supplying a constant quantity of the motive fluid. The fluid motors 46, 57 and 58 may be of any suitable type of low pulsation characteristics whereby to develop a driving torque proportional to the pressure of the motive fluid. To adapt the edger rolls 4, finishing rolls 5 and the take-up reel 30 each to be driven with a predetermined torque, relief valves 61, 62 and 63 are provided in the individual hydraulic drives for governing the pressure of the motive fluid therein. As illustrated in the drawings, the manually adjustable relief valves 61, 62 and 63 are arranged in branch conduits 64, 65 and 66 connecting the high pressure conduits 50, 55 and 56 with the exhaust manifold 51. The relief valves may be of any suitable type for maintaining a constant pressure of the motive fluid in the conduits 50, 55 and 56 for any particular adjustment by bleeding the motive fluid from the conduits at a predetermined pressure, such a valve being generally similar to that shown and described in detail in United States Letters Patent to Charles M. Terry, No. 1,863,075, issued June 14, 1932. As each of the relief valves 61, 62 and 63 is independently adjustable the pressure of the motive fluid in the hydraulic drives may be controlled individually whereby to drive the edger rolls 4, finishing rolls 5 and the take-up reel 30 with predetermined constant torques slightly in excess of the rolling or winding effort, as the case may be, to adapt them to accommodate their speed to the speed of the stock while maintaining the tension on the stock between the units substantially constant throughout a rolling operation.

One embodiment of a rolling mill incorporating

the present invention having been described in detail, the mode of operation of the complete mill is as next explained.

The break-down rolls 3, edger rolls 4 and finishing rolls 5 are first adjusted to give the proper successive reduction in the stock and the relief valves 61, 62 and 63 are screwed down tightly to provide a maximum pressure of the motive fluid supplied to the fluid motors 46, 57 and 58 whereby to drive the reduction rolls and the wind-up reel units with a maximum torque. The stock is then threaded through the set of break-down rolls 3, edger rolls 4 and finishing rolls 5 by intermittently starting and stopping the electric motors 39 and 41 by means of the switch 42 and the end of the stock is attached to the drum 33 of the take-up reel 30.

The mill is then ready for a rolling operation and the speed of the stock through the mill is controlled by the adjustment of the variable speed motor 39 for driving the break-down rolls 3. After the switch 42 is closed the stock advances through the mill and is acted upon by the break-down rolls 3, edger rolls 4 and finishing rolls 5 to reduce the stock to the desired shape and size. The break-down rolls 3 are driven directly by the electric motor 39 and the edger rolls 4, finishing rolls 5 and take-up reel 30 are driven from the motor 41 through the individual hydraulic drives comprising the pumps 45, 53 and 54, fluid motors 46, 57 and 58 connected to the drive shafts 26, 27 and 36, and conduits 50, 55 and 56 connecting the respective pumps and motors. The pumps 45, 53 and 54 supply the motive fluid under pressure to the motors 46, 57 and 58 and the latter, being of a type in which the torque developed is directly proportional to the pressure of the motive fluid, they drive their respective reduction roll and take-up reel units with a predetermined constant torque corresponding to the setting of the relief valves.

After the mill has been started the relief valve 61 in the branch conduit 64 connecting the high pressure conduit 50 and exhaust manifold 51 of the hydraulic drive for the edger rolls 4 is turned manually to adjust the pressure of the motive fluid to a value at which the edger rolls 4 are driven with a torque only slightly in excess of the rolling effort. To this end the relief valve 61 is adjusted gradually to reduce the pressure of the motive fluid in the conduit 50 until slack appears in the stock between the break-down rolls 3 and edger rolls 4. The relief valve 61 is then adjusted in the opposite direction with a predetermined slight increment of movement to increase the pressure of the motive fluid to a value at which the motor will drive the edger rolls 4 with a constant torque slightly in excess of the rolling effort to produce a predetermined tension in the stock between the break-down rolls 3 and edger rolls 4.

The relief valves 62 and 63 are also adjusted in the same manner as explained with respect to the relief valve 61 to drive the finishing rolls 5 and the take-up reel 30 with a torque slightly in excess of the rolling or winding effort to produce a predetermined constant tension on the stock between units. As the fluid motors 46, 57 and 58 drive the edger rolls 4, finishing rolls 5 and the take-up reel 30 with a predetermined constant torque the speed of the units may vary without affecting the adjustment of the units or the tension of the stock between units. Stated otherwise, the individual hydraulic drives for the sep-

arate units of the rolling mill may be adjusted in accordance with the present invention to vary the torque of the reduction roll and the wind-up reel units whereby numerous advantages result including convenient and quick adjustment of the units and the maintenance of a tension on the stock between units.

Although the hydraulic drive for the take-up reel 30 is shown in Figs. 1 to 4 as of the same type as that used on the edger rolls 4 and finishing rolls 5 the tension on the stock between the finishing rolls and reel will decrease slightly during a winding operation due to the increase in diameter of the superimposed layers of stock on the drum as it is wound thereon. In other words, the hydraulic drive for the take-up reel 30 operates to drive the reel drum 33 with a constant torque, which is the product of the moment arm and force applied, whereby any increase in the diameter of the layers of the stock or the moment arm of the reel drum due to the winding of the stock thereon causes the force or tension on the stock applied at the end of the moment arm to decrease in proportion.

In accordance with the present invention when certain kinds of stock are to be processed, a constant horsepower fluid motor is preferably provided for driving the take-up reel 30 to maintain a substantially constant tension between the last set of reduction rolls 5 and the reel. One form of constant horsepower hydraulic drive for the take-up reel 30 is illustrated in Fig. 5 as comprising a constant displacement pump 68 driven by the prime-mover 41 and a variable displacement fluid motor 69. The pump 68 draws the motive fluid from a tank 70 and delivers it through a conduit 71 to the fluid motor 69, the latter discharging the motive fluid through the exhaust conduit 72 back to the tank 70. The fluid motor 69 may be of any suitable type such as illustrated and described in United States Letters Patent to Walter Ernst, No. 2,021,353, issued November 19, 1935. Suffice it to state herein that the displacement of such a fluid motor 69 may be varied from zero to its maximum by relatively shifting its rotor laterally. In the patented construction shift-rods are provided for relatively shifting the rotor while in the present construction a piston 73 is provided at one side of the rotor for shifting it laterally in one direction and a spring 74 is provided at the opposite side of the rotor opposing the action of the piston and operative to shift the rotor laterally in the opposite direction. With such a variable displacement motor 69 the horsepower developed is directly dependent upon the amount and pressure of the motive fluid passing therethrough and the speed of the motor is dependent upon the relative position of its rotor. The piston 73 is connected to the high pressure conduit 71 through an adjustable bleeding relief valve 75 and conduit 76 whereby fluid under pressure escaping through the relief valve and conduit operates the piston to increase the displacement of the motor to decrease its angular speed. As the amount of motive fluid bleeding through the relief valve 75 and conduit 76 is relatively small it will not materially affect the amount of motive fluid passing through the motor and the pressure of the fluid will be maintained substantially constant by continually adjusting the displacement of the motor whereby to maintain a constant horsepower.

The speed of the motor 69 is controlled by the speed of the stock through the mill. If the displacement of the motor 69 is so adjusted that

it tends to operate at a higher speed the momentary resistance offered by the stock is transmitted back through the motor to increase the pressure of the motive fluid. Such instantaneous increase in the pressure of the motive fluid causes it to escape through the bleeding relief valve 75 and conduit 76 and operate the piston 73 to increase the displacement of the motor and thereby decreases its speed. The conduit 76 and piston 73 are so constructed as to permit the motive fluid bled through the relief valve 75 to gradually leak or escape whereby the motive fluid is continuously bled and its instantaneous pressure determines the instantaneous adjustment of the motor. As the diameter or moment arm of the reel drum 33 increases due to the winding of the stock thereon the displacement of the motor is increased automatically to decrease its angular speed without varying the amount or pressure of the motive fluid, the decrease in speed being in direct proportion to the increase in the moment arm to maintain a constant tension on the stock. In other words, the motor develops a constant horsepower but its displacement and speed is continuously and automatically controlled to maintain a constant tension on the stock.

In Fig. 6 another form of constant horsepower hydraulic drive for the take-up reel 30 is illustrated in which the relationship of the pressure and amount of motive fluid passing through the motor are automatically controlled to maintain a constant tension on the stock. This form of hydraulic drive comprises a constant displacement fluid pump 78 and constant displacement fluid motor 79 connected in the same manner as the pump and motor illustrated in Fig. 5. An adjustable bleeding relief valve 80 is provided in a branch conduit 81 leading from the high pressure conduit 82 back to the tank 83. The adjustable relief valve 80 may be of any suitable type as explained with respect to the relief valves 61, 62 and 63 and as herein illustrated it comprises a ball 84 yieldingly pressed against a valve seat 85 by a compression spring 86. The compression or resistance of the spring 86 is adjusted by a slidable block 87 having a stem 88 projecting upwardly through the valve casing. A lever 89 pivoted intermediate its ends has one end bearing against the end of the valve-stem 88 and a feeler 90 at its opposite end bearing against the stock being wound on the reel drum 33.

Without any control means the speed of the constant displacement motor 79 depends upon the amount of motive fluid passing therethrough and the horsepower is dependent upon the amount and pressure of the motive fluid passing therethrough. To decrease the speed of the fluid motor 79 to compensate for the increase in diameter of the stock winding on the reel drum 33 part of the motive fluid must be bled through the relief valve 80. As the speed of stock controls the speed of the fluid motor 79 the instantaneous resistance will cause the fluid to escape through the bleeding relief valve 80. However, to maintain a constant tension on the stock the horsepower of the motor must be maintained constant by increasing the pressure of the motive fluid.

During the winding of the stock on the reel drum 33 the lever 89 is rocked on its pivot to increase the compression of the spring 86 in proportion to the increase in diameter of the stock on the wind-up drum and thereby proportionally increase the pressure of the motive fluid in the conduit 82 to maintain a constant horsepower as the speed of the fluid motor decreases. In other

words, the pressure of the motive fluid is controlled in direct relationship to the increase in diameter of the stock winding on the drum 33 to maintain a constant horsepower and thereby a constant tension on the stock.

Fig. 7 illustrates a still further modified form of constant horsepower hydraulic drive for the take-up reel 30. In this form of hydraulic drive a variable displacement pump 92 is provided of the same type as the fluid motor 69 illustrated in Fig. 5. The fluid motor 93 is of a constant displacement type whereby its speed and the speed of the reel drum 33 connected thereto is dependent upon the amount of motive fluid passing therethrough and the horsepower is dependent upon the amount and pressure of the fluid passing therethrough. The piston 94 for adjusting the displacement of the pump 92 is connected to the high pressure conduit 95 through a branch conduit 96. A spring 97 at the opposite side of the pump 92 opposes the action of the piston 94. The motive fluid exhausting from the fluid motor 93 discharges into a supply tank 98 from which it is drawn to the pump 92.

With this latter form of hydraulic drive for the take-up reel 30 the pump 92 supplies a predetermined amount of motive fluid to drive the fluid motor 93 at the same speed as the stock to apply a predetermined tension thereon. As the stock winding on the reel drum 33 increases in diameter the tension on the stock is transmitted back through the fluid motor 93 to cause an instantaneous increase in the pressure of the motive fluid which, acting through the branch conduit 96, operates the piston 94 to alter the displacement of the pump 92 against the action of the spring 97 whereby to decrease the amount of fluid supplied to the fluid motor. Thus, the angular speed of the fluid motor 93 is diminished in direct proportion to the increase in diameter of the stock winding on the take-up reel drum 33. However, the compression of the spring 97 opposing the piston 94 with the parts in equilibrium results in an increase in pressure of the motive fluid proportional to the decrease in speed of the motor to maintain a constant horsepower and thereby a constant tension on the stock. In other words, the gradual increase in the compression of the spring 97 effects a gradual increase in the pressure of the motive fluid to compensate for the decrease in the amount of fluid supplied by the pump 92 to maintain a constant horsepower.

The present invention also contemplates hydraulic driving means for relatively traversing the take-up reel and stock to wind the latter in superimposed layers of closely adjacent coils as illustrated in Figs. 8 and 9. In this form of drive the take-up drum 100 of the reel is mounted on the end of a shaft 101 adapted for sliding movement. The shaft 101 is driven by a worm-wheel 102 which, in turn, is driven by a worm 103, the shaft being provided with a spline 104 to adapt it for longitudinal sliding movement with respect to the worm-wheel. The opposite end of the shaft 101 extends into a cylinder 105 and has a piston 106 at its end.

Motive fluid is supplied to the cylinder 105 alternately at one side and then at the other of the piston 106 to cause reciprocation of the shaft 101 and take-up reel drum 100 mounted thereon. The fluid circuit for the cylinder 105 comprises a pump 110 driven by an electric motor 111, the pump drawing motive fluid from a tank

112 and discharging it through a conduit 113. The motive fluid passes through an adjustable metering box or valve 114 in the conduit 113 which controls the amount of motive fluid passing therethrough at a predetermined pressure and the pressure of the fluid in the conduit is controlled by the bleeding relief valve 115 which discharges surplus motive fluid through the conduit 116 back to the tank 112. The metering valve 114 may be of any suitable type such as that illustrated and described in United States Letters Patent to T. L. Farnham, No. 2,146,537, issued February 7, 1939. The motive fluid passing through the metering valve 114 enters the casing 118 of a two-way valve through an inlet port 117. A valve plug or septum 119 in the valve casing 118 in one position of adjustment connects the inlet port 117 with a port 120 connected by a conduit 121 to the cylinder 105 at one side of the piston 106. By turning the valve plug 119 from the position shown in Fig. 8 to that shown in Fig. 9 the inlet port 117 of the valve casing is connected to a port 122 which directs the motive fluid through a conduit 123 to the cylinder 105 at the opposite side of the piston 106. The ports 120 and 122 are also alternately connected to an exhaust port 124 in the valve casing 118 as the valve plug is rocked from one to the other of its two positions illustrated in Figs. 8 and 9 so that the motive fluid is exhausted from one end of the cylinder 105 as it is being supplied to the other side. The exhaust port 124 is connected by a conduit 125 to the tank 112.

A snap-acting mechanism is provided for operating the valve plug 119 at the end of the stroke of the piston 106 and take-up reel drum 100. The snap-acting mechanism herein illustrated comprises a lever 128 pivoted intermediate its ends at 129 with one end pivotally connected to an operating arm 130 of the valve plug 119. A second lever 131 is pivotally connected at one end to the lever 128 intermediate the pivot 129 and the end connected to the operating arm 130 and its opposite end 132 is bifurcated to embrace the shaft 101 between spaced stops 133 and 134 on the latter. The lever 131 and the end of the lever 128 opposite from the one connected to the valve operating arm 130 are connected by an over-center compression spring 135.

Thus, as the shaft 101 and reel drum 100 move to the left as viewed in Fig. 8 the stop 134 acting on the bifurcated end 132 of the lever 131 rocks the latter to the position illustrated in dash-lines in Fig. 8. The lower end of the spring 135 having been moved beyond the center line of the lever 128 causes the spring to act on the lower end of said lever to rock it to the position illustrated in Fig. 9. Thus the upper end of the lever 128 is moved to the left as viewed in Fig. 9 and, due to its pivotal connection with the operating arm 130 of the valve plug 119 it rocks the latter with a snap action from the position shown in Fig. 8 to that illustrated in Fig. 9. The hydraulic driving means is thus operative to relatively traverse the reel drum 100 and stock first in one direction and then in the other to lay the stock in superimposed layers of closely adjacent coils, the control valve 119 being automatically operated to reverse the direction of traverse at the end of each stroke.

As the layers of stock build up on the reel drum 100 a greater length of stock is wound at each revolution of the drum 100. To compensate for the increase in diameter of the lay-

ers of stock on the reel drum 100 as the stock is wound thereon it is desirable to slowly diminish the rate of traverse of the drum and stock to cause the latter to be laid in closely adjacent coils throughout the winding. To this end a lever 138 pivoted intermediate its ends at 140 has a feeler projection or roller 141 at one end for engagement with the stock on the reel 100. The opposite end of the lever 138 is connected to an adjusting arm 142 of the metering box 114 through a link 143. Thus, as the diameter of the stock winding on the reel 100 increases the lever 138 is rocked in a counterclockwise direction and acting through the link 143 it operates the adjusting arm 142 of the metering box in direct proportion to the increase in diameter of the stock on the reel to decrease the amount of motive fluid flowing to the cylinder 105 and thereby diminish the speed of relative traverse of the drum 100 and the stock.

It will be observed from the foregoing specification that the present invention provides individual hydraulic drives for the several units of a rolling mill for operating the reduction rolls with a predetermined constant torque slightly in excess of the rolling effort to maintain a tension on the stock between units while permitting the speed of the reduction rolls to vary in accordance with the linear speed of the stock. It will be observed further that the invention provides a constant horsepower hydraulic drive for the take-up reel which is self-adjusting to decrease the angular velocity of the reel in proportion to the increase in diameter of the layers of stock winding on the reel. It will be observed still further that the present invention contemplates hydraulic driving means for relatively traversing the reel and stock to wind the latter in superimposed layers of closely adjacent coils with automatically operated means for decreasing the rate of traverse in proportion to the increase in diameter of the layers of stock wound on the reel drum.

While a preferred and several modified forms of hydraulic drives for the individual units of a rolling mill are herein illustrated and described, it will be understood that further modifications may be made in the form and arrangement of the hydraulic drives and in the construction of the units of the rolling mill with which they are used without departing from the spirit or scope of the invention. For example, a pressure controlled variable displacement pump may be used in the hydraulic circuit in place of the constant displacement pump and relief valve illustrated in the drawings to maintain the pressure of the motive fluid constant. Therefore, without limiting ourselves in this respect, we claim:

1. The method of rolling stock in a tandem rolling mill which comprises driving each set of reduction rolls with a predetermined constant torque and permitting the speed of said reduction rolls to vary to automatically adjust itself to the speed of the stock.

2. The method of rolling stock in a tandem rolling mill which comprises driving each set of reduction rolls with a predetermined constant torque slightly in excess of the rolling effort while permitting the speed of the rolls to vary whereby said reduction rolls automatically adjust their speed to the speed of the stock passing therebetween.

3. The method of rolling stock in a tandem rolling mill having a series of sets of reduction rolls which comprises driving each of the plu-

rality of sets of reduction rolls with a predetermined constant torque slightly in excess of the rolling effort to maintain a tension between the sets of reduction rolls while permitting the speed of the reduction rolls to vary and automatically adjust itself to the speed of the stock.

4. The method of rolling stock in a tandem rolling mill having a set of break-down rolls and a plurality of sets of reduction rolls which comprises driving the break-down rolls with an adjustable speed drive to adapt the speed of the stock through the mill to be manually controlled, and driving each set of reduction rolls with a predetermined constant torque slightly in excess of the rolling effort while permitting the speed of the reduction rolls to vary to automatically adjust itself to the speed of the stock.

5. The method of rolling stock in a tandem rolling mill having a plurality of sets of reduction rolls and a take-up reel which comprises driving each set of reduction rolls with a predetermined constant torque slightly in excess of the rolling effort to tension the stock between the sets of reduction rolls, and driving the take-up reel with a constant horsepower flexible drive to maintain a constant tension on the stock between the last set of reduction rolls and the take-up reel during the winding of the stock on the latter.

6. In a rolling mill, a set of reduction rolls, a hydraulic drive for operating said reduction rolls, and means for controlling the motive fluid of the hydraulic drive to maintain its pressure constant during a rolling operation whereby the torque applied to said reduction rolls by said hydraulic drive is maintained substantially constant at any speed of the reduction rolls.

7. In a rolling mill, a set of reduction rolls, a hydraulic motor for driving said reduction rolls, a pump for supplying motive fluid to said motor, and an adjustable pressure-responsive relief valve between the motor and said pump for controlling the motive fluid supplied to said motor to maintain a predetermined constant pressure at any particular adjustment during a rolling operation whereby the torque applied to the reduction rolls by said hydraulic drive is maintained substantially constant and the speed of the reduction rolls is permitted to vary.

8. In a rolling mill, a plurality of sets of reduction rolls arranged in tandem for simultaneously acting upon a continuous length of stock, an individual hydraulic drive for each set of reduction rolls, and means for independently controlling the motive fluid of each hydraulic drive to maintain its pressure constant during a rolling operation whereby the torque applied to each set of reduction rolls by its hydraulic drive is maintained substantially constant while permitting the speed of the reduction rolls to vary to adjust themselves to the linear speed of the stock passing therebetween.

9. In a rolling mill, a plurality of sets of reduction rolls arranged in tandem to simultaneously act upon a continuous length of stock, an individual hydraulic motor for driving each of certain of the sets of reduction rolls, a pump for supplying motive fluid to each of the motors, and means for independently controlling the motive fluid supplied to each of said hydraulic motors to maintain its pressure constant during a rolling operation whereby the torque applied to each set of reduction rolls by its hydraulic drive is maintained substantially constant and slightly in excess of the rolling effort.

10. In a rolling mill, a plurality of sets of reduction rolls arranged in tandem for simultaneously acting upon a continuous length of stock, an individual hydraulic drive for each of certain of the sets of reduction rolls comprising a fluid motor and a pump for supplying motive fluid under pressure thereto, and an adjustable relief valve in each hydraulic drive for controlling the motive fluid to maintain a predetermined constant pressure at any particular adjustment during a rolling operation whereby to maintain the torque applied to each set of reduction rolls slightly in excess of the rolling effort while permitting the reduction rolls to automatically adjust their speed to the linear speed of the stock passing therebetween.

11. In a rolling mill, a set of break-down rolls, a plurality of sets of reduction rolls, said break-down rolls and plurality of sets of reduction rolls being arranged in tandem to simultaneously act upon continuous length of stock, an adjustable speed motor for driving the set of break-down rolls, an individual hydraulic drive for each of the sets of reduction rolls, and means for independently controlling the motive fluid for each hydraulic drive to maintain its pressure constant during a rolling operation whereby to individually maintain a predetermined constant torque applied to each set of reduction rolls slightly in excess of the rolling effort while permitting the sets of reduction rolls to automatically adjust their speed to the linear speed of the stock passing therebetween.

12. In a rolling mill, a set of break-down rolls, a plurality of sets of reduction rolls, said break-down rolls and plurality of sets of reduction rolls being arranged in tandem to simultaneously act upon a continuous length of stock, an adjustable speed motor for driving the set of break-down rolls, a fluid motor for each set of reduction rolls, a pump for each fluid motor connected thereto for supplying motive fluid under pressure, and a manually adjustable relief valve between the pump and motor of each hydraulic unit for individually controlling the pressure of the motive fluid and the torque applied to each set of reduction rolls by its hydraulic drive, said relief valve maintaining the pressure of the motive fluid and torque substantially constant at any particular setting.

13. In a rolling mill, a set of break-down rolls, a plurality of sets of reduction rolls, said set of break-down rolls and plurality of sets of reduction rolls being arranged in tandem to simultaneously act upon a continuous length of stock, an adjustable speed electric motor for driving the set of break-down rolls, a fluid motor for each set of reduction rolls, a pump for each fluid motor connected thereto for supplying motive fluid under pressure, a constant speed electric motor for simultaneously driving the plurality of pumps, and a manually adjustable relief valve between the pump and motor of each hydraulic unit to individually control the pressure of the motive fluid and the torque applied to each set of reduction rolls by its hydraulic drive.

14. In a rolling mill, a plurality of sets of reduction rolls, a take-up reel, said reduction rolls and take-up reel being arranged in tandem to simultaneously act upon a continuous length of stock and wind the rolled stock on the reel, an individual hydraulic drive for each of certain of the sets of reduction rolls and the take-up reel,

and means for controlling the motive fluid of each of the hydraulic drives to maintain its pressure constant during a rolling operation while permitting the amount supplied to the motor to vary whereby to maintain a constant torque applied to each set of reduction rolls and to the take-up reel by its hydraulic drive while permitting the sets of reduction rolls and the take-up reel to automatically adjust their speed to the speed of the stock.

15. In a rolling mill, a set of break-down rolls, a plurality of sets of reduction rolls, a take-up reel, said break-down rolls, reduction rolls and take-up reel being arranged in tandem to simultaneously act upon a continuous length of stock, an adjustable speed electric motor for driving the set of break-down rolls, an individual hydraulic drive for each set of reduction rolls and the take-up reel, and means for independently controlling the motive fluid in each hydraulic drive to maintain its pressure constant during a rolling operation whereby to individually maintain a constant torque applied to each set of reduction rolls and to the take-up reel by its hydraulic drive.

16. In a rolling mill, a plurality of sets of reduction rolls, a take-up reel, said sets of reduction rolls and take-up reel being arranged in tandem to simultaneously act upon a continuous length of stock and wind the rolled stock on the reel, an individual hydraulic drive for each set of reduction rolls and for the take-up reel, means for controlling each of the hydraulic drives for the reduction rolls to maintain a constant torque applied to the reduction rolls slightly in excess of the rolling effort, and means for controlling the hydraulic drive for the take-up reel to gradually decrease the angular velocity of the reel in proportion to the increase in diameter of the layers of stock wound thereon while maintaining a constant tension on the stock.

17. In a rolling mill, a plurality of sets of reduction rolls, a take-up reel, said sets of reduction rolls and take-up reel being arranged in tandem to simultaneously act upon a continuous length of stock and wind the rolled stock on the reel, individual hydraulic drives for the separate sets of reduction rolls and the take-up reel, said hydraulic drives for the reduction rolls having constant displacement motors responsive to the pressure of the motive fluid and adjustable relief valves for maintaining the pressure of the fluid constant for any particular adjustment, said hydraulic drive for the take-up reel having a variable displacement motor in which the speed varies in proportion to the displacement, and means for controlling the displacement of the motor of the hydraulic drive for the take-up reel to gradually decrease the angular velocity of the latter in proportion to the increase in diameter of the layers of stock wound thereon while maintaining a constant tension on the stock.

18. In a rolling mill, a set of reduction rolls, a hydraulic drive for operating at least one of said reduction rolls, means for controlling the motive fluid of the hydraulic drive to maintain its pressure constant during a rolling operation whereby the torque applied to said reduction roll by said drive is maintained substantially constant at any speed of the reduction roll.
